CLAIM

The ornamental design for a packaging bag, as shown and described.

DESCRIPTION

1. Bag [packaging]
2. Bag [packaging]
- 1.1: Perspective
- 1.2: Front
- 1.3: Back
- 1.4: Top
- 1.5: Bottom
- 1.6: Right
- 1.7: Left
- 2.1: Perspective
- 2.2: Front
- 2.3: Back
- 2.4: Top
- 2.5: Bottom
- 2.6: Right
- 2.7: Left

Design 1 and 2 are packaging bags for jelly, paste or liquid contents; these packaging bags are formed by heat-sealing a part of the resin film; it has gussets at the top and bottom; the spout is placed in a part of the upper gusset; these designs (so- called variation designs) belong to groups Forming a single concept and related to each other; the parallel thin lines and the radial thin lines in the representation represent contours only and do not illustrate an ornamentation or decoration on the surface of the product.
